MULTIPLEX RADIO SYSTEM

Filed Aug. 30, 1944

UNITED STATES PATENT OFFICE

2,459,485

MULTIPLEX RADIO SYSTEM

Forrest A. Bartlett, Gardena, Calif., assignor to
Press Wireless, Inc., Chicago, Ill., a corporation
of Delaware

Application August 30, 1944, Serial No. 551,848

6 Claims. (Cl. 250—9)

1

This invention relates to multiplex radio systems and more especially to methods and means for radiating two or more messages simultaneously from a common transmitter.

A principal object of the invention relates to a multiplex radio transmitter and receiving system, wherein an existing radio service transmitter having a relatively restricted assigned or licensed frequency tolerance, can be used to transmit simultaneously a plurality of separate message signals without mutual interference at the receiving terminals.

Another principal object of the invention relates to an improved radio transmitter and receiver system of the "carrier shift" type.

A feature of the invention relates to a novel receiving system for receiving and detecting a plurality of separate messages transmitted by the "carrier shift" method.

A further feature relates to the novel organization, arrangement and relative interconnection of parts which cooperate to produce a more efficient and flexible radio service system.

Other features and advantages not specifically enumerated will be apparent after a consideration of the following detailed descriptions and the appended claims.

Inasmuch as the present invention relates to improved methods of plural message transmission from an existing transmitter, only those parts of a radio transmitter and receiver system will be schematically illustrated as are required for an understanding of the invention concept and of certain particular modes of practicing the invention. Accordingly in the drawing, there is shown in block diagram form a radio transmitter and receiver system embodying features of the invention. The invention is in the nature of an improvement on the "carrier shift" system disclosed in copending application Serial No. 498,278, filed August 12, 1943, now U. S. Patent No. 2,387,098, issued October 16, 1945, wherein a radio service transmitter, which is licensed to operate between certain well defined frequency limits, is provided with special means for effecting a "carrier shift" to represent two separate signals, e. g., "mark" and "space" (in the case of telegraphy), and "black" and "white" (in the case of facsimile). The invention is also in the nature of an improvement on the "carrier

2

shift" method of application Serial No. 502,871, filed September 18, 1943, now U. S. Patent No. 2,378,299, issued June 12, 1945.

Referring to the drawing, there is shown in composite schematic-block diagram form a transmitter and receiver wherein there are shown two separate signalling devices 1, 2, which may, for example, be telegraph keying sets, facsimile machines or a combination of both. The audio frequency signals from each of the sources 1 and 2, are applied to respective modulators 3, 4, which are supplied with high frequency oscillations from respective oscillators 5, 6. The oscillators 5, 6, are of the same normal frequency F ; and the respective modulators are arranged so that the carrier frequency F from source 5, is lowered to $(F-500)$ c. p. s., when a "mark" signal is received from source 1; and when a "mark" signal is received from source 2, the carrier frequency F from source 6 is raised to $(F+500)$ c. p. s. Therefore, the carrier frequency difference between the two channels when both are in "mark" condition, is 1000 c. p. s.

Instead of using two separate oscillators 5 and 6, and two separate modulators, a single oscillator and modulator may be employed and connected to the two sources 1 and 2, so that "mark" signals from one source raises the carrier frequency 500 c. p. s., while "mark" signals from the other source lower the carrier frequency by 500 c. p. s. A typical arrangement for this purpose is disclosed in said application Serial No. 498,278, filed August 12, 1943, now U. S. Patent No. 2,387,098, issued October 16, 1945.

The $(F+500)$ c. p. s. carrier from the first channel, and the $(F-500)$ c. p. s. carrier from the second channel are applied to any well-known radio transmitter whose final or output stages are represented by the block 7. The transmitter is tuned by means of the tuning network 8, 9, so as to cover the band $(F \pm 500)$ c. p. s.

At the receiving station, the two carriers or the single frequency-shifted carrier is applied to a converting system such as is used in heterodyne receiver comprising for example a radio frequency amplifier 10 and a mixer-converter stage 11, which is supplied with local oscillations from the crystal-controlled source 12. The output of the mixer-converter stage 11 in the well-known manner consists of intermediate frequency car-

riers representing respectively the two original signals and with a maximum frequency difference therebetween of 1000 c. p. s. The intermediate frequency carriers from device 11 are applied to a frequency multiplier 13 which, in accordance with the invention, is in the form of a harmonic generator. Preferably, this harmonic generator is of the grid-distortion electron-tube type comprising a grid-controlled electron-tube 14, whose control grid 15 operates at a positive potential for a small part of each cycle of impressed signal. For a detailed description of such a harmonic generator, reference may be had to "Radio Engineering," by F. E. Terman, first edition, page 223, published by McGraw-Hill Book Company, Inc., New York. Preferably, a parallel resonant network 16, 17, is connected in series with the grid input circuit and tuned to the desired harmonic in order to increase the output in the desired frequency range. I have found that by tuning to the tenth harmonic of the input frequency, the desired results are obtained.

Thus with the above-described frequency separation of 1000 c. p. s. between the two carriers or between the extremes of frequency-shift of the single carrier, there exists in the output of the harmonic generator 13, two carriers having a frequency separation of 10,000 c. p. s. The desired tenth harmonic must be amplified to a degree where it can be used for keying purposes, and at the same time the selectivity must be sufficient to give the necessary interchannel separation. For this purpose, the tenth harmonic signals are applied to a mixer-converter 15', which is supplied from a local oscillator 16, to reconvert the harmonic into an intermediate frequency signal which is amplified in the intermediate frequency amplifier 17'. The result is that the output of device 17' consists of an intermediate frequency carrier wherein the signal modulations representing the original signals from sources 1 and 2, have a frequency separation of 10,000 c. p. s., as distinguished from the original frequency separation of 1000 c. p. s. between the two channels at the transmitter.

The output of device 17' is applied in parallel to two second detectors 18, 19, of the beat frequency detection type, each of which has its own beat frequency oscillator 20, 21. The second detectors and their respective oscillators are arranged so that each detects by well-known beat frequency methods the respective signal modulations in the intermediate frequency carriers from amplifier 17', it being understood of course that each second detector is supplied with suitable filter means or other suppression means so that in the output of one detector the upper beat is passed to its respective audio-frequency amplifier 22, while the lower beat only from the other detector 19, is applied to its audio-frequency amplifier 23. The respective amplified signals may then be rectified in suitable rectifiers 24, 25, and applied to suitable telegraph keying or recording devices 26, 27, of well-known type. While in the foregoing specific frequencies are mentioned, it will be understood that the invention is not necessarily limited thereto but that these frequency figures are supplied merely for explanatory purposes. It will be understood of course that the invention is not limited to the transmission of two messages since more than two carriers may be simultaneously transmitted so long as the frequency limits of the two carriers is confined to the assigned or licensed service frequency band of the transmitter and the

interchannel frequency spacing at the receiver is expanded as described.

Various changes and modifications may be made in the disclosure without departing from the spirit and scope of the invention.

What I claim is:

1. In a signalling system of the carrier frequency-shift type, means to transmit from a common transmitter a plurality of carrier frequencies each representing a different signal and with the frequency difference between the carriers confined to the audio-frequency band, receiving means for said carriers comprising means to convert said carriers into corresponding intermediate frequency carriers, means to subject said intermediate frequency carriers to selective harmonic amplification to produce carriers having a frequency spacing which is a multiple of said frequency difference, means to reconvert said amplified harmonics to corresponding intermediate frequency carriers while preserving said multiplied frequency spacing, and detector means to detect in separate channels the signal modulations in the said reconverted intermediate frequency carriers.

2. In a signalling system of the carrier frequency-shift type, means to receive a carrier whose frequency is shifted a predetermined amount in one direction for one signal and a predetermined amount in the opposite direction for another signal, the maximum frequency difference of the shift being in the audio-frequency range, said means comprising in sequence a first mixer-converter for producing intermediate frequency carrier signals, a harmonic generator on which said intermediate frequency signals are impressed, means to select a harmonic from the output of said generator, a second mixer-converter for reconvert the selected harmonic into intermediate frequency signals, and a plurality of beat detectors for detecting and separating the respective modulations in the reconverted intermediate frequency signals.

3. In a carrier frequency-shift signalling system, means to receive a plurality of separate signals by a frequency-shifted carrier whose frequency excursion is in the audio-frequency range, said receiving means comprising a mixer-converter of the superheterodyne type, a harmonic generator fed from said converter means to select a harmonic of the output from said generator, and means to amplify said harmonic and to detect in separate channels the signal modulations corresponding to the upper and lower frequency limits of said shifted carrier.

4. A receiving arrangement for receiving a plurality of messages transmitted by radio carrier frequency shift and including a first converter for converting the received radio frequency carriers into corresponding intermediate frequency carriers with a frequency difference "F" cycles per second, a harmonic generator to which said intermediate frequency carriers are applied and including means to select harmonics of said intermediate frequency carriers so that the harmonic carriers have a frequency difference of nF , wherein n is greater than unity, a reconverter for changing said harmonic carriers back into intermediate frequency carriers while preserving said frequency difference nF , and means to detect said reconverted intermediate frequency carriers to derive corresponding signals therefrom.

5. A system according to claim 4 in which said harmonic generator is of the grid-distortion electron tube type.

6. A receiving arrangement for receiving two radio carrier frequencies each representing a corresponding intelligence signal, means to convert said carriers into corresponding carriers of lower carrier frequency with a frequency difference therebetween of F cycles per second, means to multiply the frequency of said lower frequency carriers to produce correspondingly higher frequency carriers with a frequency difference therebetween of nF , where n is greater than unity, means to reconver the last-mentioned carriers into corresponding but lower frequency carriers while preserving said frequency difference nF , and means to detect intelligence signals from the last-mentioned lowered frequency carriers.
